UNITED STATES PATENT OFFICE

2,007,800

DETECTOR

Joseph J. Graf, Scranton, Pa.

Application October 19, 1933, Serial No. 694,222

10 Claims. (Cl. 246—246)

This invention relates to a functionally and structurally improved signaling or detecting device.

It is an object of the invention to provide an apparatus of this character which, while capable of use in numerous different associations, is primarily intended for association with a railroad right of way, and by means of which damaged or defective, or improperly positioned units of the 10 rolling stock will be detected, and moreover, by means of which a signal will be given in response to such detection so that the condition may be remedied before an accident occurs.

A further object of the invention is that of 15 providing an apparatus of this character in which a train crew must take cognizance of such a signal indication. In other words, while the apparatus itself may include mechanisms which will of itself bring the train to a halt, it will at 20 least be necessary, according to a preferred form of the invention, that the train crew shall bring the train to a halt in order to reset the signal mechanism, thus acknowledging that such crew is cognizant of the existence of a defective or 25 damaged part.

A still further object of the invention is that of providing an apparatus of this character, the parts of which will be relatively few in number and rugged in construction, these parts being 30 capable of ready assemblage and of application to a right of way and to existing signaling mechanism, such installation being capable of being made by relatively unskilled labor and when made remaining in position without the need of 35 replacement for an indefinite period of time, or until a signal indication is given.

With these and other objects in mind, reference is had to the attached sheet of drawings, showing one practical embodiment of the invention and in which:

Figure 1 is a view showing schematically the apparatus applied to a railroad or street car right of way; and

Figure 2 is a perspective view of one of the apparatus units.

Referring primarily to Figure 1, it will be seen that the reference numeral 5 indicates rails and 6 a more or less conventional signal apparatus positioned adjacent the right of way. Associated with this signal apparatus is a special signal indicator at 7 and which may take the form of an illuminated unit or any other form of indicator, and which, when operative or energized will readily attract the attention of the 50 engineer or motorman.

With a view to operating this signal, a separate battery 8, or other source of electrical current supply may be provided. The signal is arranged in series with this source and the circuit is normally interrupted by providing a switch arm 9 which, under ordinary conditions, is in open position. The switch arm may of course be manually operated, but in addition it should be automatically operable in any one or a number of different manners. A preferred form of 10 mechanism embraces the provision of a relay of which the switch arm 9 forms a part. This relay may include a solenoid 10 cooperable with an armature 11. The solenoid is normally maintained in energized position by having its windings arranged in series with a source of electrical current supply 12, the armature 11 and one pole of the source 12 being, if desired, grounded as 15 at 13.

Thus, it is obvious that under normal conditions, and according to the present embodiment of the invention, the armature 11 is maintained in attracted condition so that the circuit through the solenoid 10 is uninterrupted. Consequently the signal 7 is normally deenergized. 20 If, however, the flow of current from the source 12 is interrupted, the armature 11, together with the switch arm 9 connected thereto will, under the influence of gravity or under the urging of a spring (not shown) be moved to a position 25 where the signal will be energized and maintained in energized condition. Moreover, even if the interruption of the circuit through the electromagnet 11 is cured, this will have no effect on the condition of the parts for the reason 30 that when the armature 11 once shifts, a manual or other actuation is necessary to bring the armature 11 into contact with the lead so that the solenoid may again be energized. Stated otherwise, if the signal 7 is energized then, ac- 35

cording to the present embodiment of the invention, it will be necessary for the motorman or engineer to bring the train or car to a halt and to manually reset the relay, thus acknowledging his awareness of a dangerous condition, 40 as will be hereinafter apparent. It is of course obvious that instead of merely energizing the signal 7, various other or additional mechanisms might be utilized to, for example, in well known manners bring the train to a halt, actuate an 45 engineer's cab signal, etc.

Interposed between the source 12 and the relay is a contact unit which may include a vertical member 14 within which there is embedded a conductor 15, the ends of which are connected 50

respectively to the source 12 and the solenoid 10. The member 14 may be supported upon cross members 16, which may be directly affixed to the ties 17. An inclined apron 18 is disposed in advance of the vertical member 14 and towards the direction of travel. Of course, if a single track is involved, and trains are liable to pass in both directions, then the apron may be duplicated on both sides of the vertical member 14.

10 In any event, the apron acts as an agent to deflect any member moving along the right of way and striking against such apron. The member 14 may be formed of any substance capable of withstanding ordinary contact and protecting the embedded conductor 15 from exposure to the elements, but at the same time fragile enough to be destroyed or injured if it is struck a violent blow. With this in mind, wood may be utilized, the plank being suitably bored to receive the conductor.

15 It will thus be obvious that the member is sufficiently rugged to withstand casual contact with tools or men engaged in ordinary work, or traversing the right of way. However, anything which will hang or drag from a passing car or locomotive, and which will have sufficient weight to endanger the train or the road bed, will break the vertical member 14. Whether a momentary grounding or an actual breakage of 20 the conductor occurs will be immaterial for the reason that in any event the circuit through the electromagnet will be either temporarily or permanently interrupted, and the armature 11 will move as aforescribed and the signal 7 will be energized.

25 Thus, it will be obvious that if a train has a broken truck or a wheel, or has any equipment loose or dragging, the signal will function, and even if the circuit through the electromagnet 30 has not been permanently impaired, the train crew will have to acknowledge the dangerous condition which exists by bringing the train to a stop and resetting the relay. Of course, where the conductor 15 has actually been broken, or 35 in other words torn apart, the unit, as viewed in Figure 2 will have to be completely replaced. The apron 18 will function to deflect sticks and other débris which may extend below the hoppers. It will also similarly deflect air and steam 40 hose couplings if these are not properly secured. Thus, only in the event of dangerous conditions will the signal 7 operate so that trains may not be unnecessarily brought to a halt.

45 In conclusion it will be appreciated that the teachings of the present invention are—as afore brought out—not necessarily limited to freight and passenger right of ways, but might be applied with facility to existing or proposed conveyors, and in fact in every installation where 50 objects are supposed to be moving along a given path and where a dangerous condition might result when various objects or parts associated therewith extend beyond such path. The claims, therefore, are to be interpreted accordingly.

55 As afore brought out, numerous changes in construction and rearrangements of the parts may be resorted to without departing from the spirit of the invention as defined by the claims.

Having described my invention, what I claim as 60 new and desire to secure by Letters Patent is:

65 1. A detector to be disposed adjacent the right of way of vehicles and including a mounting member and means supported by said member and extending adjacent the path of travel of a vehicle and in a plane to one side of the vehicle

body, whereby an object associated with said vehicle and extending beyond the normal path of travel thereof will destructively engage said means and means for deflecting casual objects away from said destructible means.

70 2. An apparatus of the character described including an electrical conductor to be connected in series with a signalling means and source of electrical current supply, and means for mounting said conductor adjacent the right of way of vehicles and to one side of the normal path of travel of the bodies thereof, whereby a portion of a vehicle body extending to one side of said normal path of travel will engage said conductor to ground or sever the same, whereby to operate 75 said signalling means.

3. An apparatus of the character described including an electrical conductor to be connected in series with a signalling means and source of electrical current supply, and means for mounting said conductor adjacent the right of way of vehicles and to one side of the normal path of travel of the bodies thereof, whereby said housing member will be engaged by any vehicle portion extending beyond the normal path of travel 20 of a vehicle and will be shattered, said signalling means operating in response to the consequent grounding or severing of said conductor.

4. An apparatus of the character described, including an electrical conductor to be connected 30 in series with a signalling means and source of electrical current supply, means for mounting said conductor adjacent the right of way of vehicles and to one side of the normal path of travel of the bodies thereof, whereby said housing member will be engaged by any vehicle portion extending beyond the normal path of travel of a vehicle 35 and will be shattered, said signalling means operating in response to the consequent grounding or severing of said conductor and means disposed in advance of said housing member to deflect casual objects from the same.

5. An apparatus of the character described including an electrical conductor to be connected in series with a signalling means and source of 40 electrical current supply, means for mounting said conductor adjacent the right of way of vehicles and to one side of the normal path of travel of the bodies thereof, whereby said housing member will be engaged by any vehicle portion extending beyond the normal path of travel of a vehicle 45 and will be shattered, said signalling means operating in response to the consequent grounding or severing of said conductor and means whereby said signal may again be rendered inoperative.

6. An apparatus of the character described including a detector member to be disposed adjacent a vehicle path and to be destructively engaged by a vehicle having portions of its body extending to one side of said path, a relay electrically connected to said detector and functioning in response to a destructive contact between the same and a vehicle portion and a signal operating in response to a functioning of the latter.

7. An apparatus of the character described including a detector member to be disposed adjacent a vehicle path and to be destructively engaged by a vehicle having portions of its body extending to one side of said path, a relay electrically connected to said detector and functioning in response to a destructive contact between the same and a vehicle portion, a normally inoperative signal and means connecting said signal to said relay to render the former operative in response to a functioning of the latter.

8. An apparatus of the character described including a detector member to be disposed adjacent a vehicle path and to be destructively engaged by a vehicle having portions of its body

5 extending to one side of said path, a relay electrically connected to said detector and functioning in response to a destructive contact between the same and a vehicle portion, a normally inoperative signal, means connecting said signal to said

10 relay to render the former operative in response to a functioning of the latter and said relay being manually resettable to deenergize said signal.

9. A detector to be disposed between the rails of a railroad right of way and within the space normally cleared by the under side and associated parts of traffic units traversing such rails, said detector including a mounting member lying between such rails, and signal controlling means associated with said member whereby a portion of

15 one of such traffic units which extends improp-

20 erly beyond the under side of the same will destructively engage said mounting member to cause a functioning of said signal controlling means.

10. A detector to be disposed between the rails of a railroad right of way and within the space normally cleared by the under side and associated parts of traffic units traversing such rails, said detector including a mounting member lying between such rails, signal controlling means associated with said member whereby a portion of one of such traffic units which extends improperly beyond the under side of the same will destructively engage said mounting member to cause a functioning of said signal controlling means, a signal connected to said controlling means and responding to a functioning of the same, and means for manually resetting said signal subsequent to such functioning.
